H. J. COOK & H. E. MARSDEN.
DEVICE FOR ROTATING PNEUMATIC DRILLS.
APPLICATION FILED MAY 19, 1914.

1,152,882.

Patented Sept. 7, 1915.

UNITED STATES PATENT OFFICE.

HENRY J. COOK, OF LOS ANGELES, CALIFORNIA, AND HERBERT E. MARSDEN, OF OTTUMWA, IOWA.

DEVICE FOR ROTATING PNEUMATIC DRILLS.

1,152,882.

Specification of Letters Patent. Patented Sept. 7, 1915.

Application filed May 19, 1914. Serial No. 839,641.

To all whom it may concern:
Be it known that we, HENRY J. COOK and HERBERT E. MARSDEN, citizens of the United States, residing, respectively, at Los Angeles, in the county of Los Angeles and State of California, and Ottumwa, in the county of Wapello and State of Iowa, have invented new and useful Improvements in Devices for Rotating Pneumatic Drills; and we do hereby declare the following to be a full, clear, and exact description of the invention, such as will enable others skilled in the art to which it appertains to make and use the same.

15 This invention relates to devices for rotating pneumatic drills.

The object of the invention resides in the provision of a device of the character named through the instrumentality of which a 20 pneumatic drill may be rotated during the operation of drilling to assure a perfectly round hole being drilled and which will enable a horizontal hole to be drilled without the use of a hollow bit.

25 A further object of the invention resides in the provision of a device of the character named which can be readily associated with a drill of ordinary construction.

With the above and other objects in view 30 the invention consists in the details of construction and in the arrangement and combination of parts to be hereinafter more fully described and particularly pointed out in the appended claims.

35 In describing the invention in detail reference will be had to the accompanying drawings wherein like characters of reference denote corresponding parts in the several views, and in which—

40 Figure 1 is a view in elevation of a pneumatic drill having the attachment associated therewith; Fig. 2, a longitudinal section of what is shown in Fig. 1; Fig. 3, an enlarged section on the line 3—3 of Fig. 1; Fig. 4, an 45 enlarged section on the line 4—4 of Fig. 1; Fig. 5, a perspective view of the sleeve embodied in the device and which interlocks with the air feed piston of the drill so that rotation of the sleeve will produce a corresponding rotation of the air feed piston, and 50 Fig. 6, a perspective view of the key members which are attached to the sleeve.

Referring to the drawing A indicates generally a pneumatic drill which includes an 55 air feed cylinder 10, an air feed hollow pis-

ton 11, a body 12, operating mechanism 13 within the body, and a drill 14.

The improved device is shown as comprising a tubular member B formed of sections 15 and 16 provided with flanges 17 60 whereby said sections may be bolted together upon the drill. The central portion of the bore of the tubular member B is enlarged as at 18 for a purpose that will presently appear. The improved device further 65 embodies a sleeve 19 engaged upon the air feed piston 11 and having fixed thereon a worm wheel 20. This sleeve 19 is rotatably disposed in the tubular member B with the worm wheel 20 working in the enlarged portion 18 of the bore of said tubular member. One end of the sleeve 19 is provided with a flange 21 disposed exteriorly of the tubular member B and having secured thereagainst 70 segmental plates 22 provided with keys 23 which engage in grooves 24 formed in the air feed piston 11 and whereby the rotation of said sleeve will effect a corresponding rotation of the air feed piston 11, body 12 and drill 14. Journalled in the tubular member B 75 and extending transversely thereof is a shaft 25 which has fixed thereon within the enlarged portion 18 of the bore of the tubular member a worm 26 meshing with the worm wheel 20. Fixed on the shaft 25 exteriorly of the tubular member is a crank 27 whereby 80 said shaft may be rotated to effect a rotation of the sleeve 19. It will be observed in this connection however that any other suitable means may be employed to rotate the 85 shaft 25.

In the operation of the drill it will be obvious that when air is admitted to the cylinder 10 the piston 11 will be forced longitudinally so as to move the drill 14 up to the work. The operating mechanism within the body 13 will of course be actuated in the usual manner. With the parts thus set in operation it will be obvious that upon effecting rotation of the shaft 25 the piston 11, body 12 and drill 14 will be rotated.

What is claimed is:

1. The combination with a pneumatic drill including an air feed cylinder and an air feed piston disposed within the cylinder, 105 said piston being provided with a longitudinal groove, a tubular member fixed to the air feed cylinder, a sleeve rotatably mounted in the tubular member, a key carried by said sleeve and engaged in said groove 110

whereby the sleeve and piston are non-rotatably and slidably connected, and means for rotating said sleeve.

2. The combination with a pneumatic drill including an air feed cylinder and an air feed piston movable within the cylinder, said piston being provided with a longitudinal groove, a tubular member fixed to the air feed cylinder, a sleeve rotatably mounted in the tubular member, a sectional ring secured to one end of the sleeve and having a key engaged in said groove whereby the sleeve and piston are non-rotatably and slid-

ably connected, and means for rotating said sleeve.

In testimony whereof, we affix our signatures, in the presence of two witnesses.

HENRY J. COOK.
HERBERT E. MARSDEN.

Witnesses for Cook:

G. C. FARMER,
AMIE L. MOLLER.

Witnesses for Marsden:

FRANK R. WILLIAMS,
A. P. MURPHY.
